Primary Examiner — Janice Hallmark*(74) Attorney, Agent, or Firm* — McGarry Bair PC**CLAIM**

The ornamental design for a ceiling fan light shade, as shown and described.

DESCRIPTION

FIG. 1 is a top perspective view of a ceiling fan light shade; FIG. 2 is a bottom perspective view of the ceiling fan light shade of FIG. 1;

FIG. 3 is a top view of the ceiling fan light shade of FIG. 1; FIG. 4 is a bottom view of the ceiling fan light shade of FIG. 1;

FIG. 5 is a front side view of the ceiling fan light shade of FIG. 1;

FIG. 6 is a rear side view of the ceiling fan light shade of FIG. 1;

FIG. 7 is a left side view of the ceiling fan light shade of FIG. 1; and,

FIG. 8 is a right side view of the ceiling fan light shade of FIG. 1.

Portions of the ceiling fan light shade shown in broken lines form no part of the claimed design. The oblique shade lines in the drawings indicate a transparent appearance.

1 Claim, 6 Drawing Sheets(56)
